VARIABLE COUPLING DEVICE

Robert L. Sprout, Princeton, N. J., assignor to
Radio Corporation of America, a corporation of
Delaware

Application February 26, 1946, Serial No. 650,369

2 Claims. (Cl. 178—44)

1

This invention relates generally to microwave apparatus and more particularly to improved variable-coupling wide-frequency-band tunable microwave resonators of the type utilizing a movable piston wherein adjustment of the piston for tuning the resonator simultaneously adjusts the coupling characteristics of a coupling loop projecting into the resonator.

It has been customary to utilize adjustably tuned microwave resonators as frequency controlling or filter elements in microwave generators, mixers and transmission systems. The resonant frequency of such microwave resonators may be varied by longitudinal adjustment of a conductive piston enclosed within the resonator shell. Well known methods of coupling into or out of such adjustable resonators include the use of microwave probe elements, coupling loops and adjustable aperture devices, depending upon the characteristics of the circuit to which the resonator is coupled. It is frequently advantageous to be able to vary the degree of coupling between an external circuit and the microwave resonator as the resonator is tuned through its useful frequency band. In particular in reflex oscillators of the type including an electron reflecting electrode, it is desirable that the coupling coefficient between the oscillator and the load circuit remain substantially constant or decrease as the oscillator frequency is increased. A conventional coupling loop, probe or aperture device coupled into the oscillator cavity normally will provide an increased coupling coefficient as the frequency is increased, thereby providing non-linear loading of the oscillator over its useful frequency range.

The instant invention is related to and comprises an improvement over the devices disclosed in the copending U. S. application of Ernest G. Linder, Serial No. 650,710, filed February 27, 1946, covering several embodiments of microwave apparatus wherein the frequency of a microwave resonator is varied by longitudinal adjustment of a piston operative therein, and wherein the effective length of a microwave coupling probe, or the angular displacement of a coupling loop as well as the effective opening of an aperture device is simultaneously adjusted by movement of the tuning piston. The invention as disclosed therein provides means for tuning a microwave generator and simultaneously adjusting the coupling thereto from an external coaxial line or waveguide device.

In contradistinction thereto, the instant invention comprises a variable-coupling wide-frequency-band microwave coaxial line resonator

2

including a movable piston having an aperture therein disposed within and between the resonator conductors. A coupling loop of uniform cross-section terminates a coaxial line connected to an external device. The loop extends through the resonator and through the aperture in the tuning piston. Longitudinal adjustment of the tuning piston thus controls the resonator frequency and the coupling coefficient of the loop in opposite sense. Since there is no contact between the loop and the movable piston, the commonly erratic characteristics of movable contacts at microwave frequencies is eliminated insofar as coupling is concerned. A modification of the invention utilizes a coupling loop having a tapered cross-section wherein the coupling coefficient changes in accordance with a predetermined non-linear function of the resonant frequency of the resonator.

20 Among the objects of the instant invention are to provide an improved method of and means for simultaneously adjusting the tuning and coupling of a microwave resonator device. Another object of the invention is to provide a method and means for tuning a coaxial microwave resonator over a relative wide frequency range and for simultaneously adjusting the coupling coefficient of a coupling element connected to an external circuit. A further object of the invention is to provide an improved coaxial microwave resonator including a longitudinally adjustable tuning piston, wherein adjustment of the piston simultaneously adjusts the effective coupling to the resonator of a microwave coupling loop. 25 Another object is to provide an improved coaxial microwave resonator including a longitudinally adjustable tuning piston, wherein adjustment of the piston simultaneously adjusts the effective coupling of a microwave coupling loop having a predetermined tapered conformation for coupling an external circuit to said resonator according to a predetermined function of the operating frequency.

An additional object is to provide an improved 30 variable-coupling wide frequency band microwave resonator including a frequency adjusting piston wherein adjustment of the tuning piston simultaneously varies in opposite sense the resonant frequency of said resonator and the coupling coefficient of a coupling loop coupling said resonator to an external circuit. A further object is to provide a constant-coupling wide-frequency-band microwave resonator including a movable tuning piston wherein adjustment of the tuning piston varies the resonant frequency of said reso-

resonator without substantial variation of the coupling coefficient of a loop coupling said resonator to an external circuit.

The invention will be described in greater detail by reference to the accompanying drawing of which Figure 1 is a cross-sectional elevational view of a first embodiment of the invention; Figure 2 is a plan, partially cross-sectional view along the section line II-II of the device shown in Figure 1; and Figure 3 is a cross-sectional, elevational view of a second embodiment of the invention. Similar reference characters are applied to similar elements throughout the drawing.

Referring to Figures 1 and 2 of the drawing, a typical microwave resonator according to the invention includes inner and outer coaxially disposed conductors 1, 3, wherein the outer conductor includes a closed end portion 5. The resonator is tuned by means of a longitudinally adjustable piston 7 having an aperture 9 disposed therein in the region intermediate the inner and outer coaxial line conductors. The longitudinal adjustment of the piston 7 may be accomplished by means of actuator bars 10 connected to any desired type of actuating mechanism not shown. The piston 7 includes a pair of cylindrical slotted contact elements 11, 13, which contact the outer and inner resonator conductors, respectively, to insure uniform electrical contact with the piston.

A second coaxial line having an outer conductor 15 and an inner conductor 17 is terminated within the tunable resonator by means of a "hairpin" coupling loop 19. The coupling loop 19 extends through the portion of the resonator intermediate the end face 5 and the tuning piston 7 and also extends through the aperture 9 in the tuning piston 7.

Thus, as the resonant frequency of the resonator 1 is increased by advancement of the piston face toward the end resonator wall 5, increasingly shorter portions of the coupling loop are exposed to the resonator cavity, thereby correspondingly tending to reduce the coupling between the resonator and the external coaxial line 15, 17. The coupling from the masked portion of the loop through the aperture 9 to the resonator cavity is practically negligible. Depending upon the circuit parameters, the coupling coefficient to an external circuit, not shown, may be maintained substantially constant throughout the useful frequency range of the resonator, or the coupling coefficient may be reduced as the frequency is increased. Since the loop does not contact the movable piston and is fixed with respect to the resonator walls, erratic operation due to varying contact resistances is minimized.

The device illustrated in Figure 3 is similar to that described by reference to Figures 1 and 2, with the exception that the coupling loop 19' is of non-linear cross-section, whereby longitudinal adjustment of the tuning piston 7 varies the coupling coefficient of the coupling loop 19' according to a non-linear function of the operating frequency of the resonator. It should be understood that the shape of the coupling loop 19' may be varied in accordance with the desired coupling coefficient characteristic to provide either constant coupling or variable coupling in opposite

sense to the variation of the resonant frequency of the resonator as the piston position is adjusted.

It should be understood that the variable- or constant-coupling systems disclosed herein may be employed as either output or input coupling elements for associated circuits and that simultaneous or separate control of a plurality of such coupling elements may be provided for a single resonator or for a plurality of resonators. By proper proportioning of the adjustable resonator and the associated coupling loop or loops, the coupling coefficient to external circuits may be maintained substantially constant or varied in opposite sense to the adjustment of the resonator frequency.

Thus, the invention disclosed comprises several embodiments of coaxial resonator wide-frequency-band microwave devices providing tuning and frequency variation by adjustment of a tuning piston, wherein such piston adjustment provides corresponding control of the coupling coefficient between said resonator and an external circuit.

I claim as my invention:

1. A constant coupling wide-frequency-band tunable microwave resonator including a coaxial line section, means including a movable piston having an aperture therethrough disposed within and substantially conforming to said section and comprising with said line section said tunable resonator, and a U-shaped coupling loop extending into said resonator through the wall of said resonator opposite said piston and having a U-shaped portion of said loop extending through said aperture in said piston for microwave coupling to said resonator, whereby adjustment of said tuning piston varies the resonant frequency of said resonator and the coupling coefficient to said resonator of said coupling loop in predetermined relative sense and degree.

2. A constant coupling wide-frequency-band tunable microwave resonator including a coaxial line section, means including a movable piston having an aperture therethrough disposed within and substantially conforming to said section and comprising with said line section said tunable resonator, and a U-shaped coupling loop of predetermined tapered width extending into said resonator through the wall of said resonator opposite said piston and having a U-shaped portion of said loop extending through said aperture in said piston for microwave coupling to said resonator; whereby adjustment of said tuning piston varies the resonant frequency of said resonator without substantial variation of the coupling coefficient to said resonator of said coupling loop.
